UNITED STATES PATENT OFFICE.

WILLIAM C. IRVIN AND FREDERICK M. DOAK, OF SAN FRANCISCO, CALIFORNIA.

METALLIC WATER-FLUME.

1,168,505.

Specification of Letters Patent. Patented Jan. 18, 1916.

Application filed October 28, 1914. Serial No. 869,030.

To all whom it may concern:

Be it known that we, WILLIAM C. IRVIN and FREDERICK M. DOAK, citizens of the United States, residing in the city and county of San Francisco and State of California, have invented certain new and useful Improvements in Metallic Water-Flumes, of which the following is a specification.

The hereinafter described invention relates to that class of water flumes commonly employed in connection with the work of irrigation or the conducting of water as a flowing stream to distant points, and wherein the flume or water-way comprises a plurality of open metallic sections united one to the other and ordinarily suspended within an open supporting frame structure.

The object of the present invention is to permit of light metal being utilized from which to construct the flume sections and to so unite or connect the ends of adjacent sections of the respective flume sections of the water-way that provision will be provided at such transverse joints for the free expansion of the connected sections, and in general to provide a water flume simple in its construction, inexpensive, durable, and less liable to leakage than with the open metallic flumes as at present constructed.

To comprehend the invention reference should be had to the accompanying sheet of drawings, wherein—

Figure 1 is a broken perspective view, disclosing a portion of a completed water-flume constructed under the invention. Fig. 2 is a broken detail longitudinal sectional view illustrating the manner of uniting the ends of adjacent flume sections and the tie members therefor. Fig. 3 is a detail plan view disclosing one of the angle plates attached to the flume structure and to which plates the ends of the outer supporting tie members are keyed. Fig. 4 is a transverse section of a flume-way, illustrating the super-structure for preventing spreading of the frame structure. Fig. 5 is a broken longitudinal sectional view taken on line $\alpha-\alpha$ Fig. 4 of the drawings, and viewed in the direction of the arrow. Fig. 6 is a broken transverse sectional view taken through the flume at the point of union of adjacent flume sections.

In the drawings, the numerals 1 and 2 are used to designate adjacent flume sections, preferably composed of what is known in the art as light metal and of a length suitable for open flume construction. Each sheet or section is properly curved or shaped for the desired flume-way and the ends of each metallic section terminate in a transverse substantial V-shaped or trough flanged extension, lip or section, in the present case the under surface of the said flanged extension, lip or section 3 of the flume section 1, loosely resting or nesting within the groove or channel of the flanged extension, lip or section 4 of the flume section 2, so that when the flume sections are brought together the ends of adjacent sections will interlock or engage with each other to provide a loose transverse lap joint union therebetween. Each flume section is further provided at each of its ends with a transverse expansion bend, 3' and 4' in Fig. 2 of the drawings, formed in the metal of the flume section, between the straight or body portion thereof and the transverse channeled extension, the function of said expansion bend being to give or flex sufficiently to absorb all longitudinal contraction or expansion of the section. These flume sections are held between and supported in the present case within a suitable frame structure extended the length of the flume-way, said frame structure consisting of the spaced longitudinally disposed uprights 5, tie braces 6 and the longitudinally disposed stringers or girders 7. To the longitudinal stringers or girders 7, at each transverse joint or union between adjacent flume sections, the clamp plates 8 are secured by the lag-screws 10, and the overlapping ends of adjacent flume sections are held together transversely between the members 11 and 12, which constitute the tie members for the flume sections and for holding the same within the frame structure of the flume.

The under member 11, hereinafter termed an angle member, is suitably curved and shaped to the desired width and depth of the flume, and the said angle member in its upper face is provided with a V-shaped trough or channel 13 throughout the length thereof, into which fits or rests the under flanged lap extension or lip 4 of the flume

section 2, the shape of the said groove, trough or channel 13 of the angle member 11 being such relative to that of the lap extensions or lips 3 and 4, as to leave a transverse clearance space a between the upper edge portion a' of the channel 13 and the under face of the lap extensions 3 and 4 adjacent the expansion bends 3' and 4' respectively of the assembled flume sections 1 and 2 for the free longitudinal expansion and contraction thereof.

The ends of the angle member 11 extend through an angle opening 14 cut in the clamp plates 8 and are held thereto and to the frame structure of the flume by means of a key 14' driven through a transverse elongated opening 14² in each projecting end of the angle member 11 and which, as driven home, draws the angle member in position and holds the same to the frame structure. In the present case the securing key 14' is illustrated as a split wedge, the open members of which after the wedge key has been driven home may be spread apart or separated to prevent the same working loose.

Prior to drawing the angle member 11 into final position, the companion member 12, which is provided with a substantially wedge shaped under portion 12' is fitted within the groove formed by the flanged extension 3 of the flume section 1, the upper ends of said member bearing against the under surface of the downwardly projected flanged extension 10' of the clamp plate 8. This member 12 serves as a fillet for the channel of the flanged extension 3 and the same shall hereinafter be referred to as a fillet rod, which fillet rod is suitably curved and shaped to the desired width and depth of the flume section into which it is to lie. With the parts thus loosely assembled, the wedge keys 14' are driven home, causing the angle member 11 to force the overlapping flanged extensions of the adjacent flume sections firmly into place and securing the same between the fillet member 12 and the angle member 11, thus securely supporting the same in position throughout the length of the flume, and by reason of the support given by the said angle member 11 and the comparative shortness of the flume members 1 and 2, a durable, inexpensive and quickly constructed metallic flume is provided for and one wherein the flume sections may be composed of comparatively light iron.

The described flume construction is mainly designed for flumes of that class known as shallow flumes, but the invention is not to be understood as being so limited, inasmuch as deep flume construction may be utilized, as illustrated by Fig. 4 of the drawing.

It is desirable at times that means be em-

ployed to prevent the spreading of the frame structure, and for this purpose there is utilized a superstructure composed of a transverse tie-rod 15 united to the side longitudinal sills or girders 7 of the frame structure by the standards or uprights 15' bolted or otherwise secured thereto. These superstructures are preferably placed along the flumeway at points where the transverse joint unions between the flume sections are made, thus reinforcing the flumeway at such points and preventing the weight of the water spreading apart the frame structure of the flume and by so doing overcoming the sagging of the flume sections. The transverse tie-rod is raised or situated such a distance above the flumeway as to overcome floating débris, such as branches of trees, etc., becoming entangled therewith, which entanglement would prevent the free flow of water.

By reason of the manner of interlocking the flanged ends of adjacent flume sections and securing the same one within the other, by means of the angle member 11 and the fillet member or rod 12, a substantially non-leaky union is obtained between the flume sections, while at the same time ample provision is provided for expansion of the said flume sections, which is an important feature in connection with flume construction.

The ease with which the flume members may be assembled, materially reduces the expense incident to the installation of a flume system, while the fact that the weight of the flume is uniformly distributed throughout the length thereof overcomes danger of sagging of the united flume sections, and further, by reason of the interlocking of the ends of adjacent flume sections and the securing of the same in the manner described, separation of the flume sections in case there should be a sagging thereof by reason of the weight of the water passing therethrough, is provided against.

Having thus described the invention what we claim as new and desire to secure by Letters Patent is:

A water flume, the same comprising a supporting structure, a plurality of metallic flume sections situated within the sphere of the supporting structure, the ends of each section terminating in substantially a V-shaped flanged extension providing a transversely grooved surface and the end flanged extension of adjacent flume sections overlapping for engagement one with the other, a transversely disposed fillet member fitted within the groove of the uppermost end flanged extension of the united flume sections, a transversely disposed angle member arranged beneath the lowermost end flanged extension of adjacent flume sections and within which the same rests, the longitudinal sills or girders of the frame structure being bolted or otherwise secured to the angle member.

members being spaced from the joint of the V-shaped flanges of the main flume portions whereby a longitudinal expansion and contraction of the flume sections is permitted, 5 and means for securing the said angle member to the supporting structure whereby the interlocked end flanged extension of adjacent flume sections will be clamped between said fillet and angle members.

In testimony whereof we have signed our 10 names to this specification in the presence of two subscribing witnesses.

WILLIAM C. IRVIN.
FREDERICK M. DOAK.
